(57) **CLAIM**

The ornamental design for a grommet, as shown and described.

DESCRIPTION

FIG. 1 is an isometric view of a top, front, and right side of an ornamental design for a grommet;

FIG. 2 is an isometric view of a bottom, front, and right side of the grommet of FIG. 1;

FIG. 3 is a right side elevational view of the grommet of FIG. 1, the left side elevational view being an identical image thereof; and,

FIG. 4 is a front elevational view of the grommet of FIG. 1, the rear elevational view being an identical image thereof. The broken lines in the drawings illustrate portions of the grommet and form no part of the claimed design. The dash-dot-dash broken lines in the drawings define the bounds of the claim and form no part thereof.
